ANATOMIC VEIN OCCLUDER

Thomas D. Clark, Victor, Iowa

Application February 24, 1941, Serial No. 380,137

5 Claims. (Cl. 128—327)

In the practice of intravenous therapy it is the usual practice to apply a tourniquet to the patient's arm above the elbow for the purpose of retarding the return flow of blood in the superficial basilic and other veins and their tributaries, thereby causing these veins adjacent the elbow to become distended to thereby facilitate the therapeutic treatment.

The object of my invention is to provide an apparatus of simple, durable and inexpensive construction which may be readily, quickly and easily applied to a patient's arm and by the use of which the veins to be operated upon are occluded to a greater degree than can be produced by the application of a tourniquet and at the same time the soft tissues adjacent the patient's elbow will be drawn away from the area in which the veins to be treated are located, thereby causing the veins to be more clearly visible, and, also, at the same time gripping and holding said portions of the veins against lateral movements, thereby greatly facilitating an intravenous therapy treatment.

In the accompanying drawing—

Figure 1 shows a side view of the anatomic vein occluder, a portion of the body being broken away;

Figure 2 shows a top or plan view of same;

Figure 3 shows a vertical longitudinal sectional view of same showing a patient's arm in its initial position within the apparatus;

Figure 4 shows a similar view showing the patient's arm in an extended position and the flexible suction cup and its tissue-compressing flange in position for occluding the veins in the side of the arm opposite the elbow;

Figure 5 shows a sectional view on the line 5—5 of Figure 4;

Figure 6 shows a top or plan view of same showing the veins in the patient's arm occluded and held against lateral movement;

Figure 7 shows a sectional view on the line 7—7 of Figure 1; and

Figure 8 shows a side view, partly in section, showing an auxiliary cup which may be used for reducing the size of the suction cup.

The apparatus comprises a base, indicated generally by the reference numeral 10. Its upper surface is preferably arched longitudinally, as shown. At its top central portion it is formed with an oval opening at 11.

Secured within the body is an oval suction cup 12, preferably formed of rubber and having a base portion 13 secured within the body by a bolt 14, or otherwise. Surrounding the lower portion

of the cup 12 is a pad 15 of yielding material such as sponge rubber.

When pressure is applied to the inner central portion of the cup 12 it will be depressed, and when pressure is applied to the upper end portions of the cup the pad 15 will be depressed and the cup will become elongated somewhat flattened out and relatively shallow, as shown in Figure 4.

At the upper edge of the cup 12 is a tissue-compressing and vein-gripping flange 16 completely surrounding the cup and extended inwardly toward the center of the cup. The upper edge of the cup is arched longitudinally, as shown in Figure 1.

15 At each opposite side edge of the cup I apply a stiffening plate 17 made of thin spring metal and connected to the cup by rivets or otherwise. The ends of the plates 17 are spaced apart at the ends of the cup and are connected by contractile coil springs 18.

The patient's arm, is shown, is indicated by the reference numeral 19, the forearm 20, the elbow 21, and the veins 22.

The hospital using my apparatus should have 25 different sizes of cups for different sized patients. I have, however, provided for adapting a large sized cup for a patient of relatively smaller proportion by providing a supplemental rubber cup 23 having a flange 24 at its top, projected both 30 outwardly and inwardly. This may be placed in the main cup and will thereby adapt the apparatus for a smaller sized patient.

In practical use the patient's forearm is bent 35 to position substantially at right angles to the arm, and the elbow is placed near the central portion of the cup, as shown in Figure 3. Then the arm is pressed downwardly in the cup and moved to an extended position with the forearm substantially in line with the arm. The flange 16 40 extends over portions of the superficial basilic veins in the arm above the elbow.

During the movement just described, the following results are effected: The cup is elongated, thereby causing its sides to move toward each other, the flexible spring plates 17 hold the central side portion of the cup upwardly and the springs apply pressure tending to assist in moving the sides of the cup toward each other. This causes the soft tissue-compressing and vein-gripping flange 16 to press into the tissues of the arm and forearm and form an air-tight seal at the point of engagement. As the cup is collapsed or flattened out, a partial vacuum is formed and this applies a suction to that part of the patient's skin and soft tissues below the flange, thereby

causing a stretching of the skin and soft tissues above the cup during the straightening out movement of the patient's arm. Furthermore, the flange passing over the vein will retard the circulation of the blood and enlarge the vein, and in addition, the gripping action of the flange where it crosses the vein will hold the vein against lateral movement.

I have demonstrated that with my apparatus, the veins in a patient's arm may be quickly and easily made more prominent so that they may be easily found, and that the vein is gripped and held against lateral movement, enabling the surgeon to easily penetrate it with his instruments.

I claim as my invention:

1. An anatomic vein occluder, comprising an elongated cup-shaped body of flexible resilient material shaped to receive a patient's elbow and portions of the arm adjacent thereto and having a tissue-compressing and vein-gripping flange surrounding its upper open edge and extended inwardly, said cup-shaped body and flange having such flexibility and resiliency that when a patient's elbow is pressed into the cup-shaped body and the arm extended and pressed down at the points where they engage the ends of the cup-shaped body, the side portions of said flange will be moved inwardly toward the longitudinal center of the cup-shaped body and the flange pressed against the sides of the patient's arm, and when the pressure is removed the parts will assume their first mentioned position.

2. An anatomic vein occluder, comprising an elongated cup-shaped body of flexible resilient material shaped to receive a patient's elbow and portions of the arm adjacent thereto and having a tissue-compressing and vein-gripping flange surrounding its upper open edge and extended inwardly, said cup-shaped body and flange having such flexibility and resiliency that when a patient's elbow is pressed into the cup-shaped body and the arm extended and pressed down at the points where they engage the ends of the cup-shaped body, the side portions of said flange will be moved inwardly toward the longitudinal center of the cup-shaped body and the flange pressed against the sides of the patient's arm, and when the pressure is removed the parts will assume their first mentioned position, and a yielding base member supporting the cup-shaped body.

3. An anatomic vein occluder, comprising an elongated cup-shaped body of flexible resilient

material shaped to receive a patient's elbow and portions of the arm adjacent thereto and having a tissue-compressing and vein-gripping flange surrounding its upper open edge and extended inwardly, said cup-shaped body and flange having such flexibility and resiliency that when a patient's elbow is pressed into the cup-shaped body and the arm extended and pressed down at the points where they engage the ends of the cup-shaped body, the side portions of said flange will be moved inwardly toward the longitudinal center of the cup-shaped body and the flange pressed against the sides of the patient's arm, and when the pressure is removed, the parts will assume their first mentioned position, and a flexible plate fixed to each of the long sides of the cup-shaped body near the upper edge thereof.

4. An anatomic vein occluder, comprising an elongated cup-shaped body of flexible resilient material shaped to receive a patient's elbow and portions of the arm adjacent thereto and having a tissue-compressing and vein-gripping flange surrounding its upper open edge and extended inwardly, said cup-shaped body and flange having such flexibility and resiliency that when a patient's elbow is pressed into the cup-shaped body and the arm extended and pressed down at the points where they engage the ends of the cup-shaped body, the side portions of said flange will be moved inwardly toward the longitudinal center of the cup-shaped body and the flange pressed against the sides of the patient's arm, and when the pressure is removed the parts will assume their first mentioned position, a flexible plate fixed to each of the long sides of the cup-shaped body near the upper edge thereof, and contractile springs connecting said plates at their end portions.

5. An anatomical vein occluder, comprising a substantially oval-shaped cup of flexible resilient material, the longitudinal sides at the open top being arched upwardly at their central portions, a flexible resilient inwardly extended flange surrounding the top edge of the cup, said parts being so shaped and proportioned as to receive a patient's elbow at the lower central portion of the cup, and then when the patient's arm is extended, said flange will be pressed into the skin and soft tissues of the arm sufficiently to form an airtight seal so that a partial vacuum may be maintained within the cup.

THOMAS D. CLARK.
